UNITED STATES PATENT OFFICE.

SYLVESTER J. ASBELL, OF PATERSON, NEW JERSEY.

WATER-CLOSET VALVE.

SPECIFICATION forming part of Letters Patent No. 654,377, dated July 24, 1900.

Application filed May 9, 1900. Serial No. 16,010. (No model.)

To all whom it may concern:

Be it known that I, SYLVESTER J. ASBELL, a citizen of the United States, residing in Paterson, in the county of Passaic and State of New Jersey, have invented certain new and useful Improvements in Water-Closet Valves; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to water-closet attachments, and has reference particularly to that portion of such a mechanism as is comprised in the water-distributing medium.

The object of the invention is to provide an 20 antifreezing valve for water-closets of simple, strong, and durable construction, reliable in operation, not liable to get out of order, and which valve can be easily taken apart and put together.

25 The invention consists in the improved antifreezing valve and in the combination and arrangement of the various parts thereof, substantially as will be hereinafter more fully described, and finally embodied in the clauses 30 of the claim.

Referring to the accompanying drawings, in which like characters of reference indicate corresponding parts in each of the several views, Figure 1 is a side elevation of a water-closet provided with an improved valve. Fig. 35 2 is a view, in side elevation, of the valve detached, certain portions thereof being shown in section and others removed to better illustrate the nature of my said invention; Fig. 3, 40 a vertical sectional view on the line xx of Fig. 2; and Figs. 4 and 5 detail views of certain coöoperating parts, hereinafter more fully described.

In said drawings, a represents a water-closet 45 bowl having at or near its lower portion a flange b , by means of which latter it is secured to the floor c in the usual manner. Said bowl is adapted to discharge into the waste-pipe d , which is connected to the lower end of and extends downwardly from said bowl, said waste-pipe including a crook e , disposed a suitable

distance below said bowl, all of the usual and well-known construction.

The valve i consists of a substantially-circular shell or casing j , from which project tangentially and in the same direction two parallel externally-threaded nipples e' and e^2 , and extending upwardly from said valve-casing projects a third externally-threaded nipple f' . The latter one is connected by a pipe f^2 with the top portion of the bowl a , while the former ones are connected by pipes f and g with the water-supply and the crook e , respectively. The rear wall of the casing j is flat and is provided in its central portion with an outwardly-extending boss k , into which is drilled from the inside a bore l , adapted to form the bearing for the spindlet, which penetrates the casing and also the front cover m , the latter having an externally-threaded inwardly-extending annular flange n , adapted to be screwed into the internally-screw-threaded central opening o in the front wall of the casing j . Said disk or cover m is also provided with an outwardly-extending internally-threaded sleeve or collar p , in which is adjustably arranged the bushing q , having a polygon-shaped head r and being likewise penetrated by a central bore or hole s , through which the spindle t extends.

Integral with the disk or cover m is an inwardly-projecting centrally-arranged sleeve o' (likewise penetrated by the spindle t) and bearing with its inner face against an annular projection 2 , forming a part of an arm or lever 3 , securely mounted on the spindle t and carrying at or near each end a rearwardly-extending cylindrical pin or projection 4 . Said pins or projections 4 have their free ends rounded off and are adapted to come in close proximity to the inner face of the rear wall of the casing j . On each of said pins or projections 4 is loosely mounted a sleeve 5 , having integral therewith and at right angles thereto a rod or valve-stem 6 , extending into the port i of its respective nipple e' or e^2 and carrying at its free end a valve 7 . Each valve consists of a substantially-conical plug 8 , screwed on the reduced portion 9 of the valve-stem 6 by means of a nut 10 . Each valve-stem is provided with a tapering collar 11 , whose thickness merges off

from that of the stem to approximately that of the smaller end which adjoins it of the plug 8, thus serving to guide the same to its seat in the port and obviating undue wear on said valve.

5 The free end of the spindle *t* is squared, as at *u*, and secured thereon is a lever *v*, on one arm of which is arranged a weight *w*, while the other arm is pivotally secured, as at *y*, to 10 the rod *z*, suitably guided in a lug or projection *a'* and having its upper free end bearing against the hinged seat *b'*, all as clearly shown in Fig. 1 of the drawings.

In operation when the seat *b'* is depressed 15 the lever *v* will be operated through the medium of the rod *z*, which action of the lever will produce an oscillation of the spindle *t* and of the arm or lever 3, carried thereby. Through said oscillation of the arm 3 the valve- 20 stems 6 6 will be reciprocated in opposite directions, the valve controlling the water-supply *f* will be opened, while the valve controlling the waste-pipe *g* will be closed. The water accordingly will enter the valve-casing 25 through the pipe *f* and from there will enter the bowl *a* through the flushing-pipe *f'*. When the seat is released, the lever *v* by the action of the weight *w* will be returned to its normal position, thus closing the water-supply 30 pipe and opening the drain or waste pipe *g*, allowing the water remaining in the valve-casing and in the flushing-pipe *f'* to drain off through the waste-pipe *g* into the crook *e*, as will be manifest.

35 From the foregoing it can be seen that the valve is so constructed and arranged that not a particle of water will remain in the valve-casing or valve after the flushing. Furthermore, on account of the peculiar construction of the various parts within the valve-casing said valve is rendered very durable and the getting out of order of any part of said valve is reduced to a minimum. Special attention is called to the simple connection 40 between the valve-stems and the oscillating arm or lever 3, the latter having integral therewith projecting pins coming in close proximity to the inner face of the rear wall of the casing. On said pins are loosely 45 mounted the sleeves 5 of the valve-stems 6, which sleeves space the arm or lever 3 from said rear wall. This arrangement, besides rendering said valve very strong and solid, greatly facilitates the assembling of the various parts and, furthermore, prevents the binding 50 of the latter, as will be easily understood by those familiar with the art.

Having thus fully described my invention, what I claim as new, and desire to secure by 60 Letters Patent, is—

1. In a valve structure, the combination of a valve-casing having a supply-port, a discharge-port and a drain-port, and having its rear wall flat and its front wall provided with an internally-threaded aperture or opening, a disk or cover removably arranged in said aperture or opening, a shaft or spindle penetrat-

ing said disk and revolvably mounted therein and having its inner end journaled in the rear wall of the casing, an arm or lever in the casing and securely mounted on said shaft or spindle, a pin at or near each end of said arm and projecting rearwardly at right angles therefrom, a valve-stem revolvably mounted on each pin and spacing said arm or lever from said rear wall, a valve at the free end of each valve-stem and adapted to control its respective port, and means for oscillating the spindle or shaft, all said parts substantially as and for the purposes described. 70

2. In a valve structure, the combination of a valve-casing having a supply-port, a discharge-port and a drain-port, and having its rear wall flat and its front wall provided with an internally-threaded aperture or opening, a disk or cover removably arranged in said aperture or opening, a shaft or spindle journaled in said disk or cover and also in the rear wall of the casing, an arm or lever in the casing and securely mounted on the shaft or spindle, a pin at or near each end of said arm and projecting at right angles toward the rear wall of the casing, a sleeve revolvably mounted on each pin and spacing said arm or lever from said rear wall of the casing, a valve-stem projecting from each sleeve, a valve at the free end of each valve-stem and adapted to control its respective port, and means for oscillating the spindle or shaft, substantially as and for the purposes described. 85

90

3. In a valve structure, the combination of a valve-casing having a supply-port, a discharge-port and a drain-port, and having its rear wall flat and its front wall provided with an internally-threaded aperture or opening, a disk or cover removably arranged in said aperture or opening, a shaft or spindle penetrat-

ing said disk and revolvably mounted therein and having its inner end journaled in the rear wall of the casing, an arm or lever in the casing and securely mounted on said shaft or spindle, a pin at or near each end of said arm and projecting rearwardly at right angles therefrom, a valve-stem revolvably mounted on each pin and spacing said arm or lever from the rear wall of the casing, a plug or valve carried by each valve-stem one side of the corresponding port and having its seating end of conical form, a tapering guiding-collar disposed on each valve-stem with its larger end adjacent the reduced or seating end of the valve or plug, the thickness of said collar merging off from that of the stem to approximately that of the adjacent end of the collar, and means for oscillating the shaft or spindle, all said parts substantially as and for the purposes described. 115

120

4. In a valve structure, the combination of a valve-casing having a supply-port, a discharge-port and a drain-port, and having its rear wall flat and its front wall provided with an internally-threaded aperture or opening,

130

a disk or cover removably arranged in said aperture or opening and provided with an outwardly - extending internally - threaded sleeve, a bushing adjustably arranged in said 5 sleeve, a shaft or spindle journaled in said bushing and disk and also in the rear wall of the casing, an arm or lever in the casing and securely mounted on said shaft or spindle, a pin at or near each end of said arm and 10 projecting rearwardly at right angles therefrom, a valve-stem revolvably mounted on each pin and spacing said arm or lever from said rear wall of the casing, a valve at the 15 free end of each valve-stem and adapted to control its respective port, and means for oscillating the spindle or shaft, all said parts substantially as and for the purposes described. 40

5. In a valve structure, the combination of 20 a valve-casing having a supply-port, a discharge-port and a drain-port, and having its rear wall flat and its front wall provided with an internally-threaded aperture or opening, a disk or cover removably arranged in said

aperture or opening and provided with an 25 inwardly-extending sleeve, a shaft or spindle journaled in said sleeve and in the rear wall of the casing, an arm or lever in the casing and securely mounted on said shaft or spindle and bearing against the inwardly-extending 30 sleeve of the disk or cover, a pin at or near each end of said arm or lever and projecting rearwardly at right angles therefrom, a valve-stem revolvably mounted on each pin and spacing 35 said arm or lever from the rear wall of the casing, a valve at the free end of each valve-stem and adapted to control its respective port, and means for oscillating the spindle or shaft, all said parts substantially as and for the purposes described. 40

In testimony that I claim the foregoing I have hereunto set my hand this 8th day of May, 1900.

SYLVESTER J. ASBELL.
